COLLAR

Morris L. Kaplan, Hazleton, and Gustav Kaplan, Harrisburg, Pa., assignors, by mesne assignments, to Trubenzing Process Corporation, New York, N. Y., a corporation of New York

Application August 17, 1936, Serial No. 96,490

1 Claim. (Cl. 2—143)

The present invention relates to collars and refers particularly to those of the folding or turn down type.

In collars of this type and particularly those which include an intermediate stiffening ply of adhesive material cemented or fused to the other plies, we have found that when the collar is pressed, there is usually formed a sharp edge which is decidedly uncomfortable and annoying to the wearer. Furthermore, the continued laundering and pressing places considerable strain on the fabric in the region of the fold, which results in a break in both the fused interliner and outer ply after a few washings. Another objection resides in the fact that with collars of this type when there is no positive means for determining the fold line, an incorrect folding and pressing frequently occurs in the laundering operation and this renders necessary a complete re-laundering due to the presence of the fused material and the permanent crease formed along the incorrect line of fold.

The present invention is designed to eliminate these objectionable features by constructing a collar having means for producing a definitely marked line of fold whereby the laundry operator may determine at a glance where the fold should be made. This materially expedites the laundering operation and improves the appearance of the laundered collar. Furthermore, the sharpness of the fold line is obviated by our arrangement as the means for determining the fold line also insures a relatively soft roll or cushioned effect at the fold which is not only comfortable to the wearer, but increases the life of the collar. An additional advantage resides in the fact that this construction provides a tie space between the collar and band which greatly facilitates the tie sliding operation.

With the foregoing and other objects in view, the invention will now be more particularly described, reference being had to the accompanying drawings wherein:

Figure 1 is a side elevation of the interliner of the preferred form of our invention,

Figure 2 is an enlarged fragmentary section taken on line 2—2 of Figure 1,

Figure 3 is a side elevation of the inner ply with the strip of paper attached,

Figure 4 is an enlarged fragmentary section taken on line 4—4 of Figure 3,

Figure 5 is a side elevation of the outer ply,

Figure 6 is a section taken on line 6—6 of Figure 5,

Figure 7 is a side elevation of the plies stitched together before being reversed,

Figure 8 is a vertical section taken on line 8—8 of Figure 7,

Figure 9 is an enlarged perspective view of one end of the collar after the plies have been reversed,

Figure 10 is a vertical section showing the plies after being turned, but before the solvent has been applied,

Figure 11 is a section similar to Figure 10 after the solvent has been applied and the plies pressed together,

Figure 12 is an enlarged fragmentary sectional view of the upper portion of the collar after the plies have been pressed together showing the arrangement of the cord and strip of paper,

Figure 13 is a view showing the neck band plies stitched to the collar, but before being turned,

Figure 14 is a view of the completed collar with the neck band portions reversed and stitched down and ready for attachment to the shirt,

Figure 15 is a side elevation of a modified form of the invention after the plies have been initially stitched together,

Figure 16 is a section taken on line 16—16 of Figure 15,

Figure 17 is a side elevation of a further modification of the invention,

Figure 18 is a section taken on line 18—18 of Figure 17,

Figure 19 is a view showing the plies reversed and being pressed and fused together, and

Figure 20 is a view showing the collar after being fused and pressed.

In forming a collar incorporating the novel features of our invention, we contemplate utilizing at least two outside plies of suitable material and an intermediate ply or interliner capable of being stiffened and adhesively secured to or fused with the other plies to form a collar of either the detached or shirt attached type. The particular formation of the stiffened ply does not form a part of this invention, but is preferably of the type composed of woven threads of a cellulose derivative. As is well known in the art, this material is normally flexible until treated or moistened with a suitable solvent which, when the collar is pressed, stiffens the interliner and adhesively secures or fuses the same to the outside plies.

In our method, we interpose along the fold line between the interliner and one of the outer plies, preferably the inner ply, a means for preventing fusing of the two plies, thus creating a

natural fold line. We prefer to secure a strip of paper tissue or other light material either to the interliner or one of the outside plies before applying the solvent, thus preventing adhesion of the interliner to the outer ply and creating an area of greater flexibility than the remainder of the fold over or top portion of the collar and facilitating the folding of the collar at this point. We preferably treat this area so as to provide a marked and natural line of fold.

Referring now to the drawings, Figures 1 to 14 illustrate the preferred embodiment of the invention wherein the numeral 10 designates the intermediate ply or interliner and 11 and 12 the inner and outer plies respectively of a collar of the attached type. In this form, the collar comprises three plies and it is to be understood that by inner ply, we mean that one which in the completed article constitutes the inner or concealed ply when the collar is folded down or over the neck band portion of the collar. Likewise, the outer ply is that one which is exposed to view and constitutes the outside ply when the collar is folded over or turned down upon the neck band portion.

Secured to one surface of the interliner 10 and somewhat adjacent its top edge is a cord 13. This cord extends substantially the entire length of the collar and, as noted in Figure 1, terminates in each instance at the notched portions 14 of the interliner. These notches are formed in the interliner for a particular purpose which will be hereinafter described. While any desired type of thread may be utilized to secure the cord 13 to the interliner, we prefer a thread 15 formed of a celanese yarn which will itself fuse and permit the proper fusing of the cord and outer ply when the plies are joined together. While a linen or cotton thread could be used, we have found that it interferes somewhat with the bonding of the outer ply and interliner and thus is not as effective or satisfactory as a thread of celanese or cellulose acetate. The inner ply 11 has secured thereto, by means of suitable stitching, a strip of thin tissue-like material 16, such as tissue paper. Similarly to the cord 13 this strip extends lengthwise of the inner ply and is of sufficient width to encompass the cord when the several plies are arranged in their final positions preparatory to fusing and connecting the collar to the neck band.

The next step in the formation of the collar comprises placing the three plies together, as shown in Figures 7 and 8, with the interliner 10 and the inner ply 11 enclosing the outer ply 12. These plies are positioned with the cord 13 and the strip of paper 16 exposed and the three plies are then secured together by suitable stitching 17. The collar is then turned inside out or reversed so that the interliner is enclosed within the inner and outer plies 11 and 12 as illustrated in Figures 9 and 10 of the drawings. It will be further observed that the strip of tissue paper 16 is now secured to the inner face of the inner ply 11 and is so positioned with respect to the cord 13 that it entirely covers the latter, that is, the cord is within the area covered by the strip. The three plies are again stitched together by a row of stitching 18 which forms a marginal border around three sides of the collar. By forming the notches 14 in each upper edge of the interliner and terminating each end of the cord in rear of each notch, folding of the cord ends in the turning operation is avoided and several thicknesses of material are eliminated at

each end; this prevents undue bulkiness of the collar at these points. If the interliner and cord were not notched in this manner, each end of the cord would be folded upon itself, as well as each extreme upper corner of the interliner. The present construction, however, dispenses with these objectionable features.

The plies are now in readiness to be fused or adhesively secured to the interliner and this may be accomplished in the usual manner, such as by moistening the plies with a suitable solvent which will render the cellulose derivative cementitious. Figures 11 and 12 illustrate the collar after the solvent has been applied and the collar is now in readiness for the next operation of attaching the neck band plies thereto. These plies comprise an inner ply 19 constituting in effect a continuation of the ply 11, an outer ply 20 and a suitable lining 21 secured to the outer ply. As shown in Figure 13, these plies may be secured to the upper portion of the collar either separately or in one operation. After the neck band applying operation, the plies 19, 20 and 21 are then reversed to the position shown in Figure 14 and a double line of stitching 22 is applied lengthwise of the collar to securely connect the neck band plies to the remainder of the collar. In this view, the collar proper is complete, that is, the fold over portion and neck band portion are in readiness to be secured to the shirt in the usual manner.

It will be observed that the lines of stitching which connect the neck band portion to the rest of the collar are spaced a slight distance from the cord 13. Thus, when the collar is laid flat during the laundering operation, this cord will be prominent through the inner ply in the form of a longitudinally extending roll and thus designate and constitute a permanent fold line which the laundry operator may follow when folding over and pressing down the collar. Furthermore, by reason of the strip of paper 16 being interposed between the inner ply and the interliner, that portion or area of the inner ply will not be fused to the interliner, with the result that there is formed an area of greater flexibility than the rest of the fused portion of the collar. This, in combination with the cord 13, permits the collar to be folded over along a definite line and with a rolled effect, as distinguished from the usual sharpened folded portion of this type of fused collar. It is to be further noted that the cord 13, which may be of linen or cotton, has an additional function in the formation of the rolled fold. When the collar is being laundered and after it is ready for pressing, that portion of the collar where the cord is stitched, is considerably thicker than the remainder of the fused portion of the collar. Consequently, the moisture or dampness will remain longer in the cord than in the rest of the collar or at least during the folding operation. This has the effect of facilitating the folding operation in that this portion of the collar is softened and will assist in making the rolled edge without placing any undue strain on the plies.

Referring now to Figures 15 and 16 there is disclosed a modified form of the invention where in a line of stitching is substituted for the cord 13. In all other respects the collar is formed in the same manner as that above described. Thus, in Figure 16, which is a view similar to Figure 8, the numerals 23, 24 and 25 represent the interliner, inner ply and outer ply respectively. The interliner is provided with a line of stitching 26

extending longitudinally thereof and the inner
ply 24 has secured thereto a strip of tissue paper
27. When these plies are turned inside out, after
being stitched together, the line of stitching will
5 be positioned within the area covered by the
paper strip 27. The plies are then fused to the
interliner and the neck band portions stitched
to the fused collar. As in the other form of the
invention, the plies of the neck band will termin-
10 ate a short distance from the line of stitching
26 and the fold line will be determined by this
line of stitching. While this fold line will not
be as pronounced as that in which the cord is
used, nevertheless, we have found that this form
15 of the invention constitutes quite an improve-
ment over the usual form of fused collar; that is,
it permits the collar to be folded over along a
definite permanent line and in addition, prevents
a sharpened folded edge, and an early breaking
20 of the plies at this point.

Figures 17 to 20 illustrate another form of the
invention in which the fold line is impressed in-
to the collar instead of being formed by a cord
or line of stitching. In this form of the inven-
25 tion the collar consists of three plies, as in the
other forms. Figure 19 discloses the plies posi-
tioned in their final form, after they had been
stitched together and reversed and are in posi-
tion to be fused or adhesively secured together.
30 In this view the numerals 28, 29 and 30 repre-
sent the outer ply, interliner and inner ply re-
spectively, with the strip of tissue paper 31 in-
terposed between the interliner and inner ply.
The numeral 32 designates a pressing mechanism
35 which is adapted to press and fuse the plies to-
gether immediately after the solvent has been
applied to the plies. It will be observed that a
cord 33 is attached to the top element of the
pressing mechanism at a point coincident with
40 the area of the strip of paper 31. As the plies
are being pressed and fused together, the cord 33
will impress a groove 34 in the inner ply of the
collar. This is clearly shown in Figure 20 which
represents the collar after it has been pressed and
45 fused together. While we have found that this
groove is not as lasting as the cord and the line
of stitching, nevertheless, it will remain in the
collar after a considerable number of washings
50 and will function in the manner of the cord and
line of stitching, that is, it will provide a positive
designated fold line which may be followed by the
laundry operator in folding the collar over the
neck band. By reason of the strip of paper form-
55 ing an area of greater flexibility than the re-
mainder of the fused portion of the collar, the
fold will have a rolled effect rather than a sharp-

ened edge, and the plies will not crack or break
at the fold.

While we have disclosed all of the forms of the
invention as being applied to a shirt attached
5 collar, it is to be understood that the invention
is readily applicable to a detached collar of the
turned down or folding type. With this latter
form of collar, the inner and outer plies and in-
terliner may of course be of a width to form both
the fold over portion and the neck band and may
10 be either of a single piece of material or of sepa-
rate pieces as desired. It is furthermore appar-
ent that while we have shown the strip of paper,
the cord and line stitching as being applied some-
what adjacent the top portions of the plies, this
15 is not an essential feature of the invention as
the fused portion of the attached collar could, if
desired, be widened and constitute a considerable
portion of the neck band, with the cord and strip
of paper being positioned substantially centrally
20 of the longitudinal edges of the collar. Further-
more, while we have designated tissue paper as
the preferred material to be used, the invention is
by no means limited to paper, as any relatively
thin material may be used in its place and func-
25 tion properly to provide the area of increased
flexibility. Likewise, the interliner need not nec-
essarily constitute a completely woven ply, but
may consist of a plurality of cellulose derivative
threads interposed between the inner and outer
30 plies. Thus, in the attached claim, the terms
inner and outer plies, are considered to cover
plies regardless of whether they constitute both
the turned down portion and neck band, either
35 in one or more sections, and in either the at-
tached or detached type of collar. Furthermore,
the term intermediate stiffening liner is con-
sidered to cover both a woven ply or a plurality
40 of spaced threads. Also, the phrase "means de-
fining the fold line of the collar" is considered
broad enough to include a cord, line of stitching,
groove or any other suitable means which could
45 be used to define the fold line.

We claim:

A folding or turn down collar comprising a
plurality of plies of fabric secured together by an
intermediate adhesive material, said adhesive
material having a cover on one surface thereof
50 covering a portion of the material to prevent the
ply adjacent to the cover from adhering in the
region of the cover to form an area of greater
flexibility than the remainder of the collar, and
means located in the flexible area and defining
55 the fold line of the collar.
